(57) **CLAIM**

The ornamental design for a golf rangefinder, as shown and described.

DESCRIPTION

FIG. 1 is a front perspective view of a golf rangefinder, according to the present invention;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof; and,

FIG. 8 is a rear perspective view thereof.

The broken line showing of the golf rangefinder is for the purpose of illustrating portions of the golf rangefinder which form no part of the claimed design.
